The ornamental design for a computer, as shown and described.

DESCRIPTION

FIG. 1 is a front, top, right perspective view of a computer showing my new design;

FIG. 2 is a rear, top, right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is a front, top, right perspective view of the computer of FIG. 1 wherein the screen portion is in the closed position;

FIG. 10 is a rear, top, right perspective view thereof;

FIG. 11 is a front elevational view thereof;

FIG. 12 is a left side elevational view thereof; and

FIG. 13 is a right side elevational view thereof.

FIG. 14 is a top plan view thereof; and

FIG. 15 is a bottom plan view thereof.

FIG. 16 is a front, top, right perspective view of a second embodiment computer showing my new design;

FIG. 17 is a rear, top, right perspective view thereof;

FIG. 18 is a front elevational view thereof;

FIG. 19 is a rear elevational view thereof;

FIG. 20 is a left side elevational view thereof;

FIG. 21 is a right side elevational view thereof;

FIG. 22 is a top plan view thereof; and

FIG. 23 is a bottom plan view thereof.

FIG. 24 is a front, top, right perspective view of the computer of FIG. 16 wherein the screen portion is in the closed position;

FIG. 25 is a rear, top, right perspective view thereof;

FIG. 26 is a front elevational view thereof;

FIG. 27 is a left side elevational view thereof;

FIG. 28 is a right side elevational view thereof; and

FIG. 29 is a top plan view thereof.

FIG. 30 is a front, top, right perspective view of a third embodiment computer showing my new design;

FIG. 31 is a rear, top, right perspective view thereof;
FIG. 32 is front elevational view thereof;
FIG. 33 is a rear elevational view thereof;
FIG. 34 is a left side elevational view thereof;
FIG. 35 is a right side elevational view thereof;
FIG. 36 is a top plan view thereof; and
FIG. 37 is a bottom plan view thereof.
FIG. 38 is a front, top, right perspective view of the computer of FIG. 30 wherein the screen portion is in the closed position;
FIG. 39 is a rear, top, right perspective view thereof;
FIG. 40 is a front elevational view thereof;
FIG. 41 is a left side elevational view thereof;
FIG. 42 is a right side elevational view thereof;
FIG. 43 is a top plan view thereof; and
FIG. 44 is a bottom plan view thereof.
FIG. 45 is a front, top, right perspective view of a fourth embodiment computer showing my new design;
FIG. 46 is a rear, top, right perspective view thereof;
FIG. 47 is front elevational view thereof;
FIG. 48 is a rear elevational view thereof;
FIG. 49 is a left side elevational view thereof;

FIG. 50 is a right side elevational view thereof;
FIG. 51 is a top plan view thereof; and
FIG. 52 is a bottom plan view thereof.
FIG. 53 is a front, top, right perspective view of the computer of FIG. 45 wherein the screen portion is in the closed position;
FIG. 54 is a rear, top, right perspective view thereof;
FIG. 55 is a front elevational view thereof;
FIG. 56 is a left side elevational view thereof;
FIG. 57 is a right side elevational view thereof;
FIG. 58 is a top plan view thereof; and
FIG. 59 is a bottom plan view thereof.
FIG. 60 is an enlarged front elevational view along the lines 60-60 of FIG. 55; and,
FIG. 61 is an enlarged front elevational view along the line 61-61 of FIG. 55.
Portions shown as broken lines are for illustrative purposes only and form no part of the claimed design. Dot-dash lines define the boundaries of, but not included in, the claimed design.
